US00D749302S

(12) United States Design Patent
Wainwright et al.

(10) Patent No.: US D749,302 S
(45) Date of Patent:  Feb. 16, 2016

(54) HEAD COVERING HAVING
DREADLOCK-LIKE APPENDAGES

(71) Applicants: Johnathon Wainwright, Memphis, TN (US); Karen Wainwright, Memphis, TN (US)

(72) Inventors: Johnathon Wainwright, Memphis, TN (US); Karen Wainwright, Memphis, TN (US)

() Term: 14 Years

(21) Appl. No.: 29/479,750

(22) Filed: Jan. 20, 2014

(51) LOC (10) Cl. 02-03

(52) U.S. Cl.

USPC D2/869

(57) CLAIM

We claim the ornamental design for a head covering having dreadlock-like appendages, as shown.

DESCRIPTION

FIG. 1 is a perspective view of an embodiment of a head covering having dreadlock-like appendages showing our new design;

FIG. 2 is a front perspective view thereof;

FIG. 3 is a rear perspective view thereof;

FIG. 4 is a right side elevation view thereof;

FIG. 5 is a left side elevation view thereof;

FIG. 6 is a top perspective view thereof; and,

FIG. 7 is a bottom perspective view thereof.
